UNITED STATES PATENT OFFICE.

LOUIS W. GORDON, OF NEW YORK, N. Y.

REMOVABLE BUCKLE HOLDER FOR SHOES.

Application filed October 21, 1926. Serial No. 143,210.

This invention relates to improvements in means for detachably mounting ornaments such as buckles onto the vamp of that class of low shoes ordinarily known as pumps.

The primary object of this invention is to provide a device which may be permanently or detachably connected to the ornament to be used, comprising means for firmly gripping the material at the edge of the vamp portion of the shoe, by spring pressure so as to insure a positive hold and a proper positioning of the buckle or other ornament.

Another object is to provide in a device of the class specified, clamping means comprising two members tending to move towards each other about a common pivotal or spring support, the distance between said clamping members and the pivotal support being sufficiently long to insure practically parallel arrangement of the two clamping members for all thicknesses of leather to be clamped therebetween.

A further object is to provide a device for detachably mounting an ornament on a shoe formed with two relatively long arms bent from a single piece of sheet steel or other metal having suitable elastic properties, providing in one unit supporting means for the ornament and clamping means therefor, the resulting device being positive and safe in its operation and being adapted furthermore to be produced at relatively low cost.

Other objects and advantages of the present invention will more fully appear as the description proceeds and will be set forth and claimed in the appended claims.

It is frequently desirable to change the style of ornament provided on a pair of slippers or pumps according to the occasion, and also according to the other articles of apparel worn at the same time. At times it is also desirable to wear the slippers or pumps without any ornament whatsoever, especially when rubbers or over-shoes have to be worn; it is therefore imperative that any device used for detachably mounting an ornament on such shoes be so designed that the outer surface of the vamp is not in the least damaged in order not to mar the appearance of the shoe.

In a broad sense, a device for removably mounting a buckle on a pump or slipper is not new, since devices of this character have been heretofore in use; but it is my ex-

perience that such devices, due to improper design do not always insure the necessary positive grip, so that the device and the ornament supported thereby may easily slip out with a possibility of their becoming lost or damaged.

At other times, I have noticed that certain similar devices found on the market can only be used in connection with shoes, the material of which has a certain definite thickness, due to the fact that the attaching members which are slipped over the edge of the vamp are set at a definite distance which admits of but very small variations; so that if the material is too thin the device is loosely inserted over it and may easily come off and if the material is too thick, the attaching members may be spread apart at such an angle that their hold is rendered very insecure.

This lack of positive action is attributable mainly to the fact that the two plates of which the attaching member is composed are obtained by bending the metal right at the point which comes in contact with the edge of the vamp proper when the device is inserted in position, a clip with but very short arms being thus formed.

The clip thus obtained is to a certain extent a spring clip, but its spring action can be but imperfectly utilized because the pivotal or spring connection of the two arms is entirely too close to the material to be clamped; so that any variation in the thickness of the material beyond a certain limit results in an excessive angular displacement of the two arms in relation to one another and consequent tendency of the device to slip out.

For a clamping device of this nature to act properly it is necessary that the pivotal or spring attachment of the two arms be set at a considerable distance from the point at which the clamping action is exerted, so that a very small angular displacement of the two arms in relation to one another is sufficient to cause a noticeable change in the distance separating the clamping portions at the ends of said arms. This insures a condition whereby the said clamping portions remain practically parallel, exerting a positive clamping action under all existing conditions, and the arrangement furthermore results in an improved gripping action and

positive hold due to the greater resiliency or springiness thus obtainable.

In the preferred type of device the gripping action is further improved by utilizing 5 the pinching effect obtained by the scissor-like action to which the material is subjected between the edges of clamping members tending to move towards one another, which are laterally displaced in relation to each 10 other. This and other points will be more clearly understood by referring to the annexed drawings in which.

Fig. 1 is a perspective view of a pump ornamented with a buckle attached thereto 15 by means of a detachable holding device;

Fig. 2 is a rear view in elevation of a buckle of conventional design;

Fig. 3 is a side sectional view in elevation through line 3—3 of Fig. 2;

20 Fig. 4 is a side view in elevation of my improved device on which a buckle is mounted showing the buckle in section;

Fig. 5 is a side sectional view in elevation of the same;

25 Fig. 6 is a front view in elevation of said device;

Fig. 7 is a rear view in elevation of the same;

30 Fig. 8 is a plan sectional view of said device through line 8—8 of Fig. 6; and

Fig. 9 is a side sectional view in elevation of a similar device permanently attached to and built as a unit with the buckle itself.

In the preferred form, the device is especially 35 designed for interchangeable use in connection with various buckles, connection between the device itself and the buckle being obtained by suitable means interlocking with the longitudinal strap bar with 40 which buckles are generally provided.

Thus in Figs. 1, 2, 3, 10 designates a conventional type of buckle provided at the rear with a relatively narrow flat bridge like bar 11 running practically for the entire 45 height of the buckle, and spaced from the rear surface of the buckle a distance 12 sufficient for the insertion of a strap or other similar holding means.

The device proper comprises an upwardly 50 directed front member 13, which is the supporting member upon which the buckle is mounted. Said front or supporting member is therefore preferably provided with a longitudinal groove 14 within which the bar 55 11 of the buckle can be inserted and retained. To this end, the device is provided with suitable means for locking the bar in position, for instance, the device may be provided with a spring finger 15 riveted at one end at 16 to the front or supporting member and extending transversely of and beyond groove 14, close to the front surface of said supporting member.

The free end of said finger is preferably 60 slightly turned outwardly, as shown at 17,

in Fig. 8, so that the bar of the buckle may be easily inserted sidewise between the said finger and the surface of the supporting member up to the point where the bar will be forced into the groove 14 by the pressure 70 of spring finger 15.

The device also comprises a rear member or arm 18 formed in one piece with the front member 13, being bent downwardly therefrom at 19, the result being a spring acting 75 clip having two arms adapted to be pressed together by hand, said two arms once more moving away from each other to their normal position when the pressure is released due to the spring action obtained by the 80 round bend 19.

An efficient spring action will, of course, be obtained by employing a suitable material such as spring steel in the manufacture of the device, so that this spring action may 85 be utilized for securely clamping the device onto the vamp of a shoe.

For this purpose, the two lower ends of members 13, 18 are caused to cross each other X fashion so that the tendency of said members or arms 13, 18 to open will be translated into a tendency in those portions thereof which project beyond the crossing point to move towards one another; so that the said extending portions will obviously exert a clamping action on anything which is inserted therebetween.

Under normal condition, the buckle must be held in an upward position slightly inclined to the rear, while the vamp of the 100 pump is also inclined upwardly from front to rear, but at a relatively small angle, the inclination thereof being closer to a horizontal than to a vertical plane. In order to obtain a proper positioning of the buckle, 105 the extreme ends of the two crossing extensions of arms 13, 18 are arranged at an angle to the supporting member or arm 13, the direction of said extensions corresponding substantially to the direction of the edge 110 portion of the vamp when said arm 13 is placed in the correct position resulting in a proper inclination of the buckle supported thereby.

The various conditions outlined are attained by bifurcating the lower end of one of the two arms of the clip, in this case the front arm or member 13, so as to produce two side projections or lugs 20, 21, and by narrowing down the lower end of the other member, in this case arm 18, so that it may pass between said lugs 20, 21, forming the desired X structure, and then by so bending and shaping said extensions that their clamping portions proper will remain in 125 the desired relative position and will be directed at the proper angle corresponding to the inclination of the edge of the vamp.

Accordingly, the two side lugs 20, 21 are first bent rearwardly and slightly upwardly 130

as shown at 22, a sufficient distance to permit the buckle carried by the device to reach a position somewhat ahead of the inner edge of the vamp, that is, the position at which 5 a buckle is usually placed; said lugs are then once more bent forwardly as at 23 and are arranged to remain somewhat inclined towards the front in order to follow more or less the normal inclination of the 10 vamp at that point as shown at 24.

The lower end 25 of arm 18 is inserted between the two rearwardly extending fractions of lugs 20, 21, and is then bent forwardly as shown at 26, at an angle substantially 15 corresponding to that of forwardly extending portions 24 of lugs 20, 21; so that normally part 26 is parallel to part 24 of lugs 20, 21 being about on a level therewith or being slightly detached therefrom, relatively 20 to a plane transversely directed to the surfaces of said parts 24, 26.

When the two arms of the clips are pressed together, surfaces 24, 26 are forced apart so that the edge of the vamp may be inserted 25 therebetween; and upon pressure on arms 13, 18, being released, the clamping portions or extensions 24, 26 will close upon said vamp edge gripping it with a firm hold sufficient to retain the device and the buckle 30 mounted thereon in position. In order to improve the clamping action, the clamping surfaces are preferably provided with burrs such as shown at 27 or with inwardly bent sharp edges such as shown at 28 or both.

35 The construction described, results in a spring having relatively long arms, where the clamping members are located at considerable distance from the point of attachment of said arms, so that but a very small angular displacement of said arms is sufficient to produce a noticeable relative movement of the said two clamping members. Accordingly, the two clamping members will remain sufficiently parallel 40 to one another irrespective of the thickness of the vamp upon which the same are inserted, providing a positive and effective clamping action at all times. The positive action of the device in this 45 respect is further insured by the fact that the spring action originates at a point far away from the end at which the clamping action is exerted; this creating a condition where no undue deformation of the spring 50 will occur at any time under practical conditions.

The central member 26 of the clamping device is slightly curved to follow the curvature of the upper part of the vamp, and the 55 two extensions 24 of the side lugs 20, 21 are inclined from front to rear in continuation of the said curvature. The metal out of which the device is made is of relatively light gauge and therefore extensions 24 will 60 fit perfectly between the vamp and the foot

of the wearer, adapting themselves to the shape of the foot without causing the slightest discomfort.

The pressure needed to operate the device for releasing the clamping action or for inserting the device in position can be conveniently exerted by holding the buckle and the holder between the first and second finger at the front and the thumb at the rear, applying pressure with the thumb against the rear arm 18. In view of the fact that these parts extend upwardly from the vamp without any hindrance at either the front or the rear, the device may be controlled at all times from a perfectly accessible point, 75 so that its speedy insertion and removal are thus assured.

It is obvious that the relative positions of the clamping ends may be inverted if desired by bifurcating the lower end of the rear arm, 80 and by causing the extension of the front arm or supporting member to cross the same between the two side extensions thereof.

In the preferred construction, the side edges of the central clamping plate 26 are 85 slightly spaced in a lateral sense from the inner edges of side plates 24 as shown in Fig. 6 leaving a relatively small clearance between the adjoining edges. This construction improves the clamping action to a considerable extent because the vamp of the shoe to which 90 the device is attached is usually made of soft, relatively pliable material, apt to yield and to bend under the clamping action of the two members, with the result that the 95 said material may bend slightly where it is clamped between adjoining edges of the lower and upper clamping plates, becoming to a certain extent wedged in between said plates.

100 This increases the frictional hold of the device upon the vamp and especially prevents in the most effective manner, possible angular displacements of the device in relation to the vamp in a transversal sense.

105 Instead of making the device detachable, the same may be built in one unit as part of the buckle itself, as shown in Fig. 9. In the same 10' designates the buckle, and 13' 110 designates the front or supporting member of the device which is permanently attached to the buckle by soldering or brazing or in any other suitable manner, or else may be made integral with the buckle itself. The remaining parts of the device are substantially 115 the same as described in connection with the previous features, 18' designating the rear arm attached to the front member by a spring 19'.

120 Like in the previous case, the said arms 125 or members 13', 18' are provided respectively with front extensions or clamping plates 26', 24', crossing each other X fashion as shown at 29. The action of this device is in every way similar to the action of the device pre- 130

viously described, and the same represents in effect a new article of manufacture in providing as it does, a buckle having means integral therewith for detachably securing said buckle in position.

My invention may be modified in its various details without departing from the spirit and scope of my invention and accordingly the drawings will be understood as being 10 intended for illustrative purposes only and not in a limiting sense. Therefore, I reserve myself the right to carry my invention into practice in all those ways and manners which may enter fairly in the scope of the 15 appended claims.

I claim:

1. An ornament supporting device for slippers, comprising two spring arms connected by a bend or loop at one end, said 20 arms crossing one another X fashion and having their free ends adapted to be inserted over the vamp of a slipper when their two connected ends are pressed together, said free ends being bent substantially in the 25 same direction transversely of said arms, and forming surfaces substantially following the outline of and adapted to clamp said vamp, securely holding the device in position when the pressure is released.
2. An ornament supporting device for slippers comprising two spring arms connected by a bend or loop at one end, one of said arms having its free end bifurcated to 30 form two spaced extensions, and the other arm having its free end crossing the former between said two extensions, the free ends of both arms being forwardly bent substantially in the same direction at an angle to said arms and forming clamping surfaces 35 adapted to register with and to follow the outline of the vamp of a slipper inserted and clamped therebetween.

3. In an ornament supporting device for slippers, the combination with a supporting 45 member, of a spring acting clamping device comprising two clamping members one of said members consisting of two spaced lateral elements and the other consisting of an element located between said two lateral 50 elements, said elements normally extending in substantially the same direction along substantially the same plane, and having their side edges close to one another, causing the material inserted between said clamping members to become wedged between said side edges.

4. A device of the class described, comprising an upwardly extending supporting member bent downwardly at its upper end 60 to form a rear spring acting arm, said supporting member having its lower end bent

rearwardly and then forwardly, and said rear arm having its lower end bent forwardly and crossing said supporting member, said forwardly extending lower ends forming 65 substantially parallel clamping surfaces adapted to be forced apart and inserted over the vamp of a slipper when said rear arm is pressed against said supporting member.

5. A device of the class described, comprising an upwardly extending supporting member, having means for the attachment of an ornament or the like, said supporting member being bent downwardly at its upper end to form a rear spring acting arm, said 75 supporting member having its lower end bent rearwardly and then forwardly and said rear arm having its lower end bent forwardly and crossing said supporting member, said forwardly extending lower ends 80 forming substantially parallel clamping surfaces adapted to be forced apart and inserted over the vamp of a slipper when said rear arm is pressed against said supporting member.

6. A device of the class described, comprising an upwardly extended supporting member, having means for the attachment of an ornament or the like, said supporting member being bent downwardly at its upper 90 end to form a rear spring acting arm, said supporting member having its lower end bifurcated to form two spaced extensions bent rearwardly and then forwardly and said rear arm having its free end bent forwardly and adapted to pass between said spaced extensions, said forwardly bent ends being adapted to be forced apart and having substantially parallel surfaces adapted to receive the vamp of a slipper therebetween 100 when said arm is forced against said supporting member.

7. A device of the class described, comprising an upwardly extending supporting member bent downwardly at its upper 105 end to form a rear spring acting arm, said supporting member having a bifurcated lower end having its side extensions bent rearwardly and then forwardly, and said rear arm having its lower end crossing said 110 extensions, said forwardly directed extensions forming clamping surfaces adapted to be inserted against the inner surface of the edge of the vamp of a shoe and the lower end of said rear arm being adapted to be inserted 115 over the outer surface of said vamp, when said rear arm is pressed against said supporting member, said vamp remaining clamped between said side extensions and said lower end of the rear arm when said 120 rear arm is subsequently released.

LOUIS W. GORDON.
